(57) **CLAIM**

The ornamental design for an adjustable clamp, as shown
and described.

DESCRIPTION

The nature and intended use of the article in which the
design is embodied is that of an adjustable clamp having
jaws that may be tightened against an object with adjustable
pressure. The pressure may be adjusted by controlling the
amount of squeezing pressure applied to handles of the
clamp.

FIG. 1 is a perspective view of an adjustable clamp showing
my new design;

FIG. 2 is a side elevational view thereof;

FIG. 3 is a front view thereof; and,

FIG. 4 is a top view thereof.
